(57) **CLAIM**

The ornamental design for a forward dumping, two-wheeled barrow, as shown and described.

DESCRIPTION

FIG. 1 is a rear perspective view of the forward dumping, two wheeled barrow according to my new design.

FIG. 2 is a top perspective view of the forward dumping, two-wheeled barrow of FIG. 1.

FIG. 3 is a side view of the forward dumping, two-wheeled barrow of FIGS. 1 and 2 in an upright position.

FIG. 4 is a side view of the forward dumping, two-wheeled barrow as in FIG. 3 in a lowered position.

FIG. 5 is a bottom view of the forward dumping, two-wheeled barrow of FIGS. 1-4; and,

FIG. 6 is a front perspective view of the forward dumping, two-wheeled barrow of FIGS. 1-5.

The design of the present invention and as shown in FIGS. 1-6 is an ornamental, forward dumping, two-wheeled barrow for use in light to medium duty applications moving gravel, dirt sand, etc. The safety/spill prevention bracket and other ornamental features present a decorative outward appearance.
